SHOE SOLE WITH CURVED GROUND-
CONTACTING FACEEugene L. Monagin, United States Navy,
Uvalde, Tex.

Application July 21, 1945, Serial No. 606,463

4 Claims. (Cl. 36—8.5)

(Granted under the act of March 3, 1883, as
amended April 30, 1928; 370 O. G. 757)

1

This invention relates to shoes and more particularly to a shoe having a substantially rigid arcuate support and ground engaging member.

Objects of my invention are to provide a device materially to reduce the fatigue of walking; to provide a means for more evenly distributing the supported weight between the heel and the ball of the foot while walking; to relieve foot arch strain; to impart the rolling action of a wheel to walking; to provide a means for bringing ease and naturalism to walking on an artificial leg; and to provide improved elements and arrangements thereof in a shoe of the character and for the purposes set forth.

In accomplishing these and other objects of the present invention, I have provided improved details of structure, the preferred forms of which are illustrated in the accompanying drawing, wherein:

Fig. 1 is a longitudinal vertical sectional view of a shoe embodying the features of the present invention.

Fig. 2 is a side elevational view of a modified form of a device embodying the features of the present invention adapted to embrace a variety of shoes to adapt the advantages of this invention to shoes of conventional design.

Referring more in detail to the drawing:

1 designates an arcuate base member of a size and material to provide a substantially inflexible rocker foundation for the shoe.

A point 2 on the base member 1 contiguous to the ball of the wearer's foot, is the point of the tangential joining of two portions of the base member having different radii of curvature.

During the normal movements of walking, the leg is pivoted respectively at the hip and at the knee. When pivoting the leg from the hip, the weight of the wearer is borne by the base member 1 between point 2 and the rear end of the base member. When the knee becomes the pivoting point, the weight is shifted forward of point 2. The radius of curvature of a wheel always being the distance from the pivot point, the axle, to the periphery of the wheel, the base member 1 is formed to have a fore and aft radius of curvature from the point 2 rearward approximating the length of the wearer's leg and a radius of curvature forward of the point 2 approximating the distance between the wearer's knee and the ball of his foot to impart the rolling action of a wheel to walking.

A ground engaging member 3 is preferably provided of suitable material on the lower side of the base member 1 to protect the base mem-

ber from wear and to act as a suitable tread portion for the shoe.

A lift 4, or wedge, is secured to the upper surface of the rearward end of the base member 1.

Fastened to the base member 1, a short distance rearward of point 2, is a shank 5 of substantially rigid construction held in spaced relation to the base member at its rearward end by being connected to and overlying the upper portion of the lift 4. The shank 5 preferably formed of metal serves as an arch support in the shoe. However, the primary arch supporting feature of this device is in the fact that the weight is transferred from the heel of the foot to the ball of the foot by the curved surface of the base member, thus relieving the arch of strain.

For the wearer's comfort, an inner sole 6 is secured by a suitable adhesive means to the upwardly exposed surface of the base member 1 and shank 5.

7 designates a back stay and 8 a counter both extended downwardly to fasten on the lift 4 and abut the base member 1. The back stay 7 and the counter 8 comprise a heel engaging and positioning means for the shoe.

The sides 9 and the toe 10 of the upper portion of the shoe extend downwardly to fasten 30 to the base member 1.

A lacing flap 11 and tongue portion 12 are provided.

The back stay 7, the counter 8, the sides 9, the toe 10, the lacing flap 11 and the tongue portion 12 comprise a substantially conventional foot receiving and positioning means for the shoe of the present invention.

Operation

40 The operation of a shoe constructed as described is as follows:

The shoe is secured to the wearer's foot in the conventional manner of inserting the foot into the foot receiving and positioning means and lacing the flaps 11.

45 In walking, the rearward portion of the ground engaging member 3 is first to bear the weight of the wearer. In striding, the first part of the step is usually made with the legs straight; all of the pivoting of the leg taking place at the hip. The portion of the base member 1 from point 2 rearward, having a radius of curvature approximating the length of the wearer's leg, provides a convenient rolling surface during the 50 first part of the step. The portion of the base

member 1 rearward of the point 2 functions as the periphery of a wheel; the wearer's leg, as a spoke of a wheel; and his hip, as a pivot point efficaciously to impart the rolling action of a wheel to walking.

As a stride progresses, the weight of the wearer of the shoe moves progressively forward on the foot. At approximately the time the weight reaches the ball of the foot the knee of the wearer starts to bend. During the completion of the stride the knee, not the hip, is the pivot point. This fact is advantageously utilized in the embodiment of this invention.

From point 2 forward, the base member 1 has a radius of curvature approximating the distance from the wearer's knee to the ball of his foot. Similarly to the first part of the stride its completion is accomplished by the portion of the base member 1, forward of point 2, acting as the periphery of a wheel; the wearer's leg and foot from his knee downward, as a spoke of a wheel; and his knee as a pivot point.

Modification

In Fig. 3, a modification of this invention is provided to the end of making the advantages incident to the use of this shoe more generally available.

In this form of the invention a base member 13 of substantially inflexible material is provided.

A point 14 in the base member 13 is in disposed relation to the ball of the wearer's foot and is the point of the tangential joining of two portions of the base member having different radii of curvature.

From the point 14 rearward to the end of the base member 13, the radius of curvature of the said base member approximates the length of the wearer's leg, as does the portion of the base member 1 rearward of the point 2 in Fig. 1.

The portion of the base member forward of the point 14 has a radius of curvature approximating the distance from the wearer's knee to the ball of his foot, similarly to the radius of curvature of the base member forward of point 2 in Fig. 1.

A ground engaging member 15 is fastened in conformity to the curvature of the downwardly disposed surface of the base member 13 preferably by suitable adhesive means.

A transverse rib 16 is provided to engage in a bracing relationship the shoe on which the device is mounted to assist in positioning and maintaining the device on the shoe in proper position.

A heel receiving portion 17 supports the heel of the shoe at a height and angle in keeping with the wearer's predetermined comfort and convenience.

A plurality of openings 18 in the heel receiving portion 17 and the base member 14, with counter sinking holes in the ground engaging member 15, comprise receptacles employed for the purpose of mounting the device on the shoe by means of screws of a length securely to engage the sole and heel of the shoe but of insufficient length to pass through the said sole and heel.

In addition, adhesive means preferably are employed on the upper surfaces of the base member 13 and the heel receiving portion 17 to assist in fastening the device to the shoe.

So mounted, the device is used as described.

It is apparent therefore, that I have provided an improved shoe that materially reduces walking fatigue, that more evenly distributes the sup-

ported weight of the wearer between his heel and the ball of his foot while walking, and imparts the rolling action of a wheel to walking.

The embodiment of this invention is particularly well suited to use on an artificial leg. The rearward and forward rolling surfaces of the shoe provide an ease and naturalism to walking by means of an artificial leg heretofore not available.

It is further apparent that by striking the extreme forward portion of this walking aid as an arc of a radius having a length extending from the ankle to the toe of the foot, this aid may also be employed to enhance the comfort of the wearer in dancing and other activities requiring bearing the wearer's weight on the toes.

The chief advantage in this device is the transfer of the wearer's weight from the heel to the ball of the foot through the aid rather than through the arch, thus alleviating possible strain on the wearer's foot.

While I have shown but certain embodiments of my invention, it is susceptible to further modification without departing from the spirit of the invention. I do not wish, therefore, to be limited by the disclosures set forth, but only by the scope of the appended claims.

The invention described herein may be manufactured and used by or for the Government of the United States of America for governmental purposes without the payment of any royalties thereon or therefor.

I claim:

1. A shoe comprising an arcuate base member having an upwardly curving rear portion described by a radius of curvature approximating the length of the wearer's leg and an upwardly curving forward portion described by a radius of curvature approximating the distance between the wearer's knee and the ball of his foot, a downwardly disposed ground engaging member secured to the arcuate base member, a lift secured to the upper surface of the said base member at its rear end to elevate the wearer's heel a distance in keeping with his predetermined walking comfort, a shank secured to the upper surface of the lift and the base member to provide support for the wearer's arch, and a shoe upper portion having side portions secured to the base member.

2. A shoe comprising a substantially rigid arcuate base member having rearward and forward upwardly curved portions of radii of curvature approximating the length of the wearer's leg and the distance between his knee and the ball of his foot respectively, a lift secured to the rear part of the base member to elevate the heel of the shoe, a shank secured to the base member and the lift to provide arch support for the wearer, and a foot receiving and positioning means supported by, and attached to, the base member, lift and inner sole assembly.

3. In a shoe, a sub-combination including an upwardly curved base member having a rear portion described by a radius of curvature approximating the length of the wearer's leg, and a forward portion described by a radius of curvature approximating the distance between the wearer's knee and the ball of his foot, a ground engaging member secured to the base member, and a lift element secured to the upper surface of the rear end of the base member to elevate the heel portion of the shoe.

4. A device attachable to a shoe comprising a

substantially rigid arcuate base member having an upwardly curved rear portion of a radius of curvature approximating the length of the leg of a person wearing the shoe and an upwardly curved forward portion of a radius of curvature approximating the distance from his knee to the ball of his foot, a downwardly disposed ground engaging wear member, an upwardly directed rib to engage the heel of the shoe and assist in maintaining the base member in proper position, and a plurality of openings in the base member provided to receive means for attaching the base member to the shoe.
